United States Patent Office

Des. 206,346
Patented Nov. 29, 1966

206,346

BROOCH OR SIMILAR ARTICLE

Theodore C. Steinman, Purchase, N.Y., assignor to Accesscraft Products Corporation, New York, N.Y., a corporation of New York

Filed July 13, 1965, Ser. No. 86,143

Term of patent 3½ years

(Cl. D45—19)

FIG. 1

FIG. 2

FIG. 3

FIG. 4

FIG. 5

FIGURE 1 is a top plan view of a brooch or similar article, showing my new design whereby the decorative beads are spherical in configuration.

FIGURE 2 is a front elevational view thereof.

FIGURE 3 is a side elevational view thereof.

FIGURE 4 is a bottom plan view thereof.

FIGURE 5 is a view similar to FIG. 2, but showing the fastening pin in elevated inoperative position.

FIGURE 6 is a front elevational view of a brooch or similar article showing an embodiment of my new design whereby the decorative beads are half round ovals in configuration.

FIGURE 7 is a side elevational view of the embodiment shown in FIG. 6.

FIGURE 8 is a rear elevational view thereof.

I claim:

The ornamental design for a brooch or similar article, substantially as shown and described.
